CLAIM

The ornamental design for a simulated torch, as shown and described.

DESCRIPTION

FIG. 1 is a rear elevation view of the simulated torch showing our new design.

FIG. 2 is a front elevation view of the simulated torch.

FIG. 3 is a left side elevation view of the simulated torch, the right side elevation view being a mirror image thereof.

FIG. 4 is a bottom plan view of the simulated torch; and,

FIG. 5 is a top plan view of the simulated torch.

The broken lines represent the portions of the design that form no part of the claim.
